UNITED STATES PATENT OFFICE.

HERBERT THOMAS HERRING, OF LONDON, ENGLAND.

ROTARY PUMP.

1,066,815.

Specification of Letters Patent.

Patented July 8, 1913.

Application filed June 4, 1912. Serial No. 701,477.

To all whom it may concern:

Be it known that I, HERBERT THOMAS HERRING, a subject of the King of Great Britain, residing at London, England, have 5 invented new and useful Improvements in Rotary Pumps, of which the following is a specification.

This invention relates to improvements in rotary pumps of the kind in which a pair 10 of toothed pistons are geared together within a suitably shaped casing, the rotation of the said pistons effecting the exhaustion, compression, or circulation of air, gas, or other fluid.

15 In the specifications of English patents granted to me dated the 13th May, 1908, and the 23rd September, 1909, and numbered 10,404 and 21,729 respectively, and in the specification of a German patent granted to 20 me No. 224,769, I have described certain devices for retaining in pumps of the above mentioned kind, especially when used for exhausting or compressing air or gas, sufficient lubricating liquid to keep, on the one hand, 25 the teeth or leaves of the pistons properly lubricated, and, on the other hand, sufficient liquid to keep the said teeth or leaves sealed, so as to prevent air or gas passing back through the pump, thereby enabling the latter to exhaust and compress air or gas more 30 effectively than heretofore, and at same time to enable the pump to be started without having to charge or prime it by hand or by special devices.

35 In the aforesaid specification No. 10,404 the means employed for these purposes consist of a by-pass pipe external to the pump; and in the aforesaid specifications Nos. 21,729 and 224,769 some of the means consist 40 of grooves or channels formed in the interior of the casing or of its covers. It is through this by-pass pipe, or through these grooves or channels, as the case may be, that the pump, when in motion, maintains a constant 45 circulation of a small portion of the said liquid from the compression or positive side of the pump to the suction or negative side thereof, a valve or other suitable device being provided for the purpose of regulating 50 the quantity of liquid circulated.

According to my present invention instead of arranging the by-passes so that they allow the small portion of liquid to flow direct from the compression chamber to the suction 55 chamber, I arrange them so that they deliver the liquid from the compression chamber

into any required number of the cells or spaces between the teeth or leaves of the pistons after the said teeth or leaves have swept past the inlet port, and have come into 60 more or less close contact with the inner surface of the pump casing.

The liquid traversing the by-passes comes in contact with the points of the advancing leaves effectually sealing the said points and 65 preventing the air or gas, already in the cells, from escaping backward toward the suction chamber. The jets of liquid issuing from the by-passes into the cells or spaces displace very little of the air or gas therefrom, but rather tend to compress such air or gas. And in order that my said invention may be fully understood, I will proceed to describe the same with the aid of the accompanying drawings, in which— 70

75 Figure 1 is a vertical section of a pump of the kind in question with my present invention applied thereto; and Fig. 2 is a section taken on the line A—A of Fig. 1.

80 *a* represents the body or casing of the pump, *b*, *b* the toothed pistons rotating in gear with each other in the said casing in the manner well understood in connection with this class of pump.

85 *c* is the outlet or delivery port from the pump casing, and *d* is the inlet or suction port leading thereto.

90 *e* is the delivery or positive pressure chamber corresponding to the chamber marked *c* in the aforesaid English specification No. 10,404 of 1908, and in the German specification No. 224,769, and containing a supply of suitable lubricating liquid *f*.

95 *g* is the suction or negative pressure chamber corresponding to the chamber marked *b* in the aforesaid English and German specifications.

100 *l* is the delivery pipe from the piston pressure chamber *e*, and *m* is the inlet pipe to the suction or negative pressure chamber *g*.

105 *h*, *h*, are by-passes arranged according to my present invention. These by-passes are so arranged that they deliver the liquid from the pressure chamber *e* into the end of any required number of the cells or spaces *i* between the teeth or leaves of the pistons after the said teeth have swept past the edges *k* of the inlet port *d*, and have come into more or less close contact with the inner surface of the pump casing, as shown in 110 Fig. 1.

As above described the liquid traversing the by-passes h comes in contact with the points of the advancing teeth or leaves, effectually sealing the said points, and preventing the air or gas already in the cells i from escaping backward toward the suction port d and chamber g .

The by-passes h are formed in the end cover of the pump and start from a recess n formed therein, as shown, with its lower edge placed at a distance equal to half the thickness of the base of a tooth or leaf, above the center line B—B joining the axis of the two pistons b — b , just where the teeth of one piston enter the cells or spaces of the other piston alternately, and where considerable power has to be exerted in ordinary pumps; not fitted with this arrangement, to force the quantity of liquid, shown by dark shading, through the very narrow clearance space p into the pressure chamber e or through the by-passes h to the cells. By this arrangement that quantity of liquid, or some of it, passes by the by-passes h into the front or first cells i endwise thereof, and at the same time causes a reduction of the power required to drive the pump. Preferably the recess n extends laterally in both directions from the center to the curved surfaces of the bodies of the pistons b from which the teeth or leaves spring; and the upper edge of the recess n may be at a distance above the lower edge equal to about the distance apart of two adjacent teeth or leaves at the root thereof, as shown in Fig. 1.

The by-passes h in the end covers may consist merely of grooves cut in the face of the cover from the recess n to the inner

curved surface of the casing as shown in Fig. 1, or they may be made as passages q 40 in the thickness of the cover, as shown in the section Fig. 2, with a short passage h at the outer end leading to the floor of the cells i .

The delivery of the liquid from between 45 the teeth or leaves into the recess n and thence to the cells below takes place alternately first one side and then the other, but always into the front or first cells.

By the employment of the above described 50 arrangement of recesses and by-passes increased mechanical efficiency of the pump is obtained as compared with pumps of this character heretofore in use.

Claim—

In a rotary pump, in combination, a casing provided with an end cover and with an inlet opening and an outlet opening, toothed pistons rotatably mounted within said casing and having their teeth intermeshing, a delivery chamber communicating with said outlet opening, a suction chamber communicating with said inlet opening, and liquid conveying passages formed in said end cover, said passages communicating with the space between the intermeshing teeth and with the spaces between adjacent teeth, and the casing on opposite sides of said inlet opening.

In testimony whereof I have signed my name to this specification in the presence of two subscribing witnesses.

HERBERT THOMAS HERRING.
